UNITED STATES PATENT OFFICE.

EDWIN T. BOOTH, OF NEW YORK, N. Y., ASSIGNOR TO LUNDBORG COMPANY, OF NEW YORK, N. Y., A CORPORATION OF NEW YORK.

DESIGN FOR A DISPLAY DEVICE.

48,771.

Specification for Design.

Patented Mar. 28, 1916.

Application filed December 8, 1915. Serial No. 65,838. Term of patent 14 years.

To all whom it may concern:

Be it known that I, EDWIN THOMAS BOOTH, a citizen of the United States of America, residing in the borough of Manhattan, city and State of New York, have invented a new, original, and ornamental Design for Display Devices, of which the following is a specification, reference being had to the accompanying drawing, forming part thereof.

The drawing is a view, in perspective, of a display device, showing my new design.

I claim:

The ornamental design for a display device as shown.

In testimony whereof, I have signed my name to this specification in the presence of two subscribing witnesses.

EDWIN T. BOOTH.

Witnesses:

THORNTON EARLL,
WILLIAM HENRY BERRIGAN.
